WIRE TREATING APPARATUS

Per Håkansson, Fagersta, Sweden, assignor to
 National Standard Company, Niles, Mich., a
 corporation of Michigan

Application September 22, 1937, Serial No. 165,067

1 Claim. (Cl. 51—140)

This invention relates to the manufacture of wire, and has particularly to do with cleaning, grinding, or polishing the surface of a wire.

In polishing any type of metal article, it is of great importance that the polishing medium move at high speed relatively to the surface on which it acts. This is difficult to accomplish in the preparation of wire for drawing, and usually the wire is merely drawn through a stationary polishing device, for example a device provided with emery acting on the surface of the wire.

This not only limits the speed, and has the disadvantage that the polishing is in the direction of the length of the wire, but (especially because of the tremendous lengths of wire which must be treated, and the fact that the surface is often greasy) the polishing medium quickly becomes dirty and loses some of its effect and must frequently be replaced. Also, in order to secure a sufficiently clean wire surface, it is often necessary to pass the wire through a device of this character more than once.

An object of the present invention is to improve the cleaning (i. e., the polishing or grinding) of wire or the like, by treating the wire with rapidly operated cleaning devices revolving around the wire as the wire is fed or drawn through the apparatus. Preferably the cleaning devices are mounted on and driven by shafts or equivalent supports, arranged to revolve about the wire.

While grinding wheels or the like may be used as such cleaning devices, I prefer to use for most purposes cleaning belts, faced with emery or chrome oxide or the like, passing over pulleys on the shafts which revolve bodily (i. e., with a planetary motion) about the wire. However, in the case of wire coming directly from a pickling operation and therefore carrying with it a corrosive material, I prefer to use brushes made of stainless steel wires.

The above and other objects and features of the invention, including various novel combinations and desirable particular constructions, will be apparent from the following description of the illustrative embodiments shown in the accompanying drawing, in which:

Figure 1 is a vertical longitudinal section through an apparatus utilizing cleaning belts;

Figure 2 is a partial vertical section therethrough on the line 2—2 of Figure 1, showing the belt arrangement;

Figure 3 is a partial section, corresponding to the right-hand portion of Figure 1, but showing

an apparatus utilizing brushes or grinding wheels; and

Figure 4 is a partial section therethrough on the line 4—4 of Figure 3.

In the illustrative apparatus of Figures 1 and 2, a wire 10 to be cleaned is drawn, by means such as a capstan 12 or the like, through a guide 14 such as a stationary sleeve mounted on the machine frame 16, and through a rotatable sleeve 18 journaled in bearings carried by posts 20 and 22 10 mounted on the frame.

The sleeve 18 is driven by means such as a belt 24 engaging fast or loose pulleys 25 or 28 on the sleeve, and driven at a relatively high speed by means such as a motor 30. The motor 15 30 may also be connected to drive the capstan 12, at a relatively low speed, through a suitable speed-reducing gear 32.

The post 22 carries, fixed thereto on one side, a stationary gear 34 coaxial with respect to the 20 sleeve 18. Immediately adjacent the gear 34, the sleeve 18 has secured thereto a cross-head 36 carrying at its opposite ends supports such as rotatable shafts 38 and 40. The shaft 38 carries a pinion 42 meshing with and rolling on the 25 gear 34, and which drives the shaft as the sleeve 18 is rotated to revolve the cross-head 36.

The shafts 38 and 40 carry a series, e. g., four each, of pulleys 44, about which pass cleaning belts 46, alternately carried on opposite sides of 30 the wire 10 in engagement therewith as shown in Figure 2. The belts 46 may be made of strips of emery cloth or the like, to serve as polishing or cleaning devices.

In the arrangement of Figures 3 and 4, the 35 shafts 38 and 40 carry grinding wheels or brushes 50 which engage the wire. If brushes are used, especially for cleaning wire coming directly from a pickling operation, I prefer to make them of wires of stainless steel (i. e., steel containing a 40 considerable amount of chromium), so they will not corrode. Since in this case there are no belts to drive the shaft 40, I provide it with a pinion 52 which meshes with and rolls on the gear 34 the same as the pinion 42.

The apparatus of Figure 1 may, if desired, be provided with means for varying the tension of the belts 46. For example, the shaft 40 may be movably mounted in a slot 58 in the cross-head 36, and journaled in a bearing 60 carried 50 adjustably by an adjusting screw 62 threaded through a lug on the cross-head.

The two shafts 38 and 40 may be braced at their outer ends by a connecting plate 64 or the equivalent. Suitable means may be provided for 55

supplying a polishing medium such as chrome oxide to the belts or brushes as they revolve and rotate.

While two illustrative embodiments have been described in detail, it is not my intention to limit the scope of the invention to those particular embodiments, or otherwise than by terms of the appended claim.

I claim:

10. Apparatus for cleaning the surface of wire or the like comprising a tubular sleeve through which the wire is adapted to pass, a cross-head rigidly carried by one end of the sleeve and terminating in an outer surface substantially flush 10
15. with said end of the sleeve, a pair of parallel shafts carried by said cross-head on diametrically opposite sides of the sleeve and projecting outwardly from said outer surface, a plurality of pulleys in abutting relationship on each of the shafts, a plurality of flexible endless wire-

cleaning belts each passing around opposite pulleys on said shafts and each arranged with its outer surface engaging the wire in such a manner that the belt is entirely on one side of the wire, adjacent belts engaging the wire on opposite sides, power operated means for driving the sleeve, a stationary driving member adjacent the cross-head, a driving member carried by one of said shafts and cooperating with the stationary driving member to drive said one of the shafts and the pulleys thereon as the sleeve and cross-head are driven, a connecting plate connecting the outer ends of the shafts, and wire guiding means outside of said connecting plate, the wire being unsupported between the sleeve and wire 15 guiding means so that the belts can be removed and replaced by removing the connecting plate without removing the wire from the apparatus.
